UNITED STATES PATENT OFFICE.

HARRY STRUGNELL, OF LANCASTER, PENNSYLVANIA, ASSIGNOR TO ARMSTRONG CORK COMPANY, OF LANCASTER, PENNSYLVANIA, A CORPORATION OF PENNSYLVANIA.

DESIGN FOR LINOLEUM OR SIMILAR HARD-SURFACED FLOOR COVERING.

Application filed October 14, 1926. Serial No. 19,331. Term of patent 7 years.

To all whom it may concern:

Be it known that I, HARRY STRUGNELL, a subject of the King of Great Britain, residing at Lancaster, county of Lancaster, and State of Pennsylvania, have invented a new, original, and ornamental Design for Linoleum or Similar Hard-Surfaced Floor Covering, of which the following is a specification, reference being had to the accompanying drawing, forming part hereof.

The figure is a plan view of a portion of linoleum or similar hard surfaced floor covering, showing my design, it being understood that the design in the representative illustration is repeated throughout the extent of the linoleum or similar hard surfaced floor covering.

I claim:

The ornamental design for linoleum or similar hard surfaced floor covering, substantially as shown and described.

HARRY STRUGNELL.
